UNITED STATES PATENT OFFICE.

WILLIAM J. WOODCOCK, OF NEW YORK, N. Y., ASSIGNOR TO REUBEN B. AYRES, OF SAME PLACE.

MEANS FOR CLOSING OR OPENING SHUTTERS.

SPECIFICATION forming part of Letters Patent No. 643,217, dated February 13, 1900.

Application filed March 17, 1899. Serial No. 709,529. (No model.)

To all whom it may concern:

Be it known that I, WILLIAM J. WOODCOCK, a citizen of the United States, residing at New York, borough of Manhattan, in the county 5 and State of New York, have invented new and useful Improvements in Means for Closing or Opening Shutters, of which the following is a specification.

This invention relates to means of electrically operating shutters for windows in buildings; and its object is to provide suitable mechanism whose moving parts are controlled and operated by an electric current and which moving parts are so arranged and connected 15 to shutters as to enable the latter to be closed or opened at will by the operation of a switch at a distant point. A building having its windows or other openings provided with shutters which are equipped with this electrical power apparatus may have such windows or openings closed instantaneously from 20 one or more common points in case of an outbreak of fire.

I am aware that various attempts have 25 hitherto been made to provide power means for operating shutters; but since the means devised have included the use of an elaborate system of piping for the conveyance of the form of power used, which besides being 30 unsightly entails considerable expense in equipment, said means have not been commercially successful, and my researches do not show that any practical form of applying electrical power has previously been proposed.

Briefly, my invention comprises a simple arrangement of pivoted arms connected to a shaft near a window, said arms being attached to the shutters, together with an armature in 40 an electrical field comprising either a permanent or electro magnet and arranged to turn the shaft, which causes the arms to close or open the shutters, as the case may be.

In the drawings accompanying this application, Figure 1 is an elevation of a pair of shutters fitted with my apparatus looking from the inside. Fig. 2 is a cross-sectional view taken on the line 2 2 of Fig. 1. Fig. 3 is a perspective view illustrating the movement of the operating parts. Fig. 4 is a sectional view of the motor employed. Fig. 5 is

a detail of the operating-arm, showing its construction; and Fig. 6 is a view of a series of window-openings provided with shutters and showing an elongated shaft extending over 55 said series of shutters, with connecting operative devices between said shaft and each of the shutters in the series.

In said figures, A indicates a window-embrasure, and B B' indicate a pair of shutters 60 and which are hinged in the ordinary manner to the wall of the building.

C indicates a horizontal shaft which is of a length to fit removably within the window-embrasure. Said shaft is fitted at each end 65 into sleeves c c, being connected to said sleeves in any suitable manner to render it rigid therewith. The sleeves c c themselves are fitted rotatably in sockets c' c', which are adjusted within the walls, as seen. The shaft 70 C lies across the window-embrasure, either centrally thereof or at its lower or upper end, as desired.

Near each end of the shaft C, upon said shaft, are securely placed collars D D', and 75 arms E E', which are connected to said collars, extend therefrom, as seen. For convenience said collars D D' and arms E E' are preferably formed in two halves, whereby they may more readily be placed about the 80 shaft and bolted thereover and because their extreme end is in the form of a socket e, which contains a ball-joint F, which latter appertains to and supports a pitman G, which serves as the operative connection with the shutter. 85 As will be observed, the opposite end of pitman G is provided with a ball-joint g, which fits within a socket H, one of which is secured upon each of the shutters B B' at a suitable point near its inner portion, whereby upon 90 the turning of shaft C the arms E E' are operated through their ball-and-socket joints to move the shutters.

It will be observed that the ball-and-socket joints are not shown in detail in the drawings and that in their construction it is necessary to provide for their proper relative play or movement, such detail, however, being readily apprehended without illustrating the same in this application as fully worked out. 95 100

It will be observed that the pitman G which is connected to the shutter B is longer than

the corresponding pitman for shutter B', the reason being that it is necessary for shutter B to close prior to the closing of shutter B' in order that the latter may overlap the former. By reason of this elongation said arms

G describe a greater radius in turning, and thereby close the shutter B more rapidly than and consequently in advance of the shutter B'.

An armature I is placed about and secured upon the shaft C, as indicated, said armature having two north poles *n n* and two south pole *s s*. Said armature is placed within the magnetic field I', having a magnet J. Electrical wires K L connect with the magnet and lead from a dynamo or batteries, (not shown,) which may be situated at any convenient point in the building. Controlling-wires M N connect with the armature and lead from an operating-switch, (not shown,) which may be situated at any suitable point in the building where most convenient to access by an operator.

In operating the device through the medium of a switch the armature is caused to rotate a quarter-turn, in so doing turning the shaft C accordingly, and thereby either opening or closing the shutters B B', as may be desired.

The electrical motor thus described may serve to operate either a shaft for one window or opening or by elongating said shaft and carrying it through or along the wall of the building the said shaft operated by a single motor may serve for closing and opening the shutters of such adjacent window or windows, as will be readily perceived. Also it is quite clear that by employing separate shafts for the shutters of adjacent windows, said separate shafts being connected by suitable gearing, in such instance likewise a single motor may serve to operate thereby the shutters of a series of adjacent windows.

While I have specifically described means whereby the shutters for a single window may be operated through the medium of a dynamo or electrical batteries and a switch at a distant point, it is of course quite obvious that by a proper system of electrical wiring and

connections a single electrical current may be transmitted at one time to actuate the shutters for a number or series of windows—as, for instance, the shutters for all the windows in a building.

The invention herein disclosed is equally applicable for closing and opening doorways or other coverings for openings of all characters in buildings, ships, and other structures—such, for instance, as bulkheads and the like—and I do not wish to be limited to any specific application of the invention, and

I claim, broadly, as follows:

1. A shutter opening and closing device comprising a rotating shaft suitably supported, pivotal connections between said shaft and the shutters and an electrical motor secured upon said shaft to turn it.

2. The combination with a window embrasure and a swinging shutter therefor, of a shaft rotatably fitted in said embrasure, a pivotal connection between said shaft and shutter a motor upon said shaft to turn it, whereby the shutter is moved; a distant electrical power apparatus, and electrical connectors between said motor and power apparatus.

3. The combination with a plurality of window embrasures each provided with shutters, of a moving body common to the same and supported adjacent thereto, and pivotal connectors between said moving body and each of said shutters, together with a single electrical motor upon said moving body to actuate it; a distant source of electrical power, and connectors therebetween.

4. The combination with a window embrasure fitted with shutters, of a turnable body bearing an armature in an electrical field to actuate said shutters.

In testimony whereof I have hereunto set my hand in the presence of two subscribing witnesses.

W. J. WOODCOCK.
